MACHINE FOR MAKING WIRE GARMENT
HANGERS

David S. Boyles, Rock Hill, S. C., assignor to
National Wire Goods Manufacturing Company,
a partnership composed of David S. Boyles,
W. J. Boyles, and J. Van Boyles

Application May 16, 1932. Serial No. 611,725

10 Claims. (Cl. 140—71)

The invention has relation to machines for making wire garment hangers, having for an object to provide an improved machine for forming the hangers proper, twisting the wire ends to form a shank, and bending the longer of said wire ends to form a hook. Another object is to provide improved means for forming the right-angle end-bends and twisting said end-bends together to form a shank. Another object is to provide improved hook forming means. Other objects and advantages will appear hereinafter.

The invention consists in the novel construction and combinations of parts as set forth in the appended claims.

In the accompanying drawings illustrating an embodiment of the invention Figure 1 is a side elevation of the machine with parts broken away; Figure 1a is a side view of the parts so broken away; Figure 2 is a top plan view of the machine 20 with parts removed and parts in section; Figure 3 is a view similar to Figure 2 on a larger scale with parts broken away and parts removed; Figure 4 is a section on the line 4—4, Figure 1; Figure 5 is a detail plan view showing the wire ends 25 of the hanger bent preparatory to twisting the same together; Figure 6 is a similar view showing the twister head in position engaging the wire ends and the same twisted together; Figure 7 is a similar view showing the hook forming head in 30 position preparatory to forming the hook in the wire end; Figure 8 is a similar view showing the twister head rotated to form the hook; Figure 9 is a detail plan view, partly broken away, of the delivery mechanism; Figure 10 is a section on the line 10—10, Figure 9; Figure 11 is a section on the line 11—11, Figure 10; Figure 12 is a detail plan view of the finished hanger and Figure 13 is a detail edge view of the same.

In these drawings, the numeral 1 designates the 40 main frame, whereon is supported a horizontal rack 2, for the wire blanks 3, cut to proper length and fed horizontally and forwardly into a vertical slot 5, having capacity to receive twelve blanks more or less, the lowermost blank 3 resting upon 45 the lower of divider blades 6, these wire blanks being released and falling downwardly one at a time by movement of operating rod 7, the forward end of which is pivoted to the lower end of arm 8, fast to and depending from rock shaft 9, 50 said shaft having fast thereto rocker lever 10, extending above and below the shaft and at its upper and lower ends having pivoted thereto links 11, two in number, the forward ends of said links being pivoted to horizontal slides, also two in number and sliding one above and in contact with the

other, the lower slide carrying the lower divider blade 6 aforesaid, and the upper slide carrying the upper divider blade 6, the rearward movement of the operating rod 7 causing the lower divider blade to be carried rearwardly to release 60 the lowermost wire blank 3 resting thereon, the upper divider blade being simultaneously carried forward beneath the vertical series of blanks 3 in the slot 5 to support said series, the lower wire blank so released falling in said slot and coming 65 to rest upon wire blank bending levers 13, of which there are two. In the reverse movement of the operating rod 7, the lower divider blade is brought forwardly beneath the lowermost wire blank to support the series of wire blanks in the 70 slot 5, and the upper divider blade is retracted from beneath the wire blanks. This wire blank feeding mechanism is disclosed in Patent #1,771,951, dated July 29, 1930.

The wire blank bending levers 13 work horizontally and are fulcrumed at 14 to the framing, being provided with upstanding projections 15, which cooperate with spaced upstanding projections 28 of the framing, and around which the wire blank end portions are bent in the operation of said levers, so that these end portions are brought towards each other, thereby forming the hanger ends A. The projections 15 at the free ends of the levers 13 constitute jaws, within notches 16 of which the adjacent end portions 85 of the wire 3 are received and clamped by means to be described so that the hanger is securely held during the twisting of the shank thereof and during the formation of the hook thereof. This clamping means also forms the bends B 90 in the upper part of the hanger adjacent the shank thereof.

The operating means for these levers 13 consists of a horizontally working slide 17, moving upon guides 18 of the framing, and having at 95 one end pivoted links 18' connecting the same with the levers 13, said slide being given reciprocatory movement by rotary shaft 19, through gearing 19' and main power shaft 20. Keyed to 100 the shaft 19 is a cam 20' having a groove wherein works a roller 21 of lever 22, to vibrate said lever upon its fulcrum shaft 23, the free end of the lever having a rod 24 connecting the same with said slide. The rod 24 has a stud 25 105 engaging one arm of a lever 26 to cause the other arm of said lever to engage stud 27 of the rod 7 to move the latter rearwardly upon forward movement of rod 24 to thereby release one wire blank 3, reverse movement of the rod 7 tak- 110

ing place under the influence of retracting spring 7'.

In order to press the lower bar of the hanger inwardly as the hanger is being bent into form, 5 slides 29 are moved forwardly to position adjacent the aforesaid projections 28 of the framing. These slides are operated by pawls 29' of levers 30, said levers being fulcrumed at 31, and having link connection 32 with lever 33, the latter 10 being fulcrumed at 34 and having its tail arm 35 engaged by the slide 17 in the rearward movement thereof to operate said lever and hold the same with the slides 29 so moved forwardly.

When the wire blank bending levers 13 reach 15 final clamping position, as shown in Figure 3, the free ends thereof cooperate with a thin blade 38 carried by frame head 37, said blade cooperating with the notches 16 of said levers to force the wire within the same and properly shape this 20 part of the hanger, the spaced opposed extremities 39 of the free or jaw ends of said levers co-operating with an upright stud or projection 41 of the framing so that in the operation of levers 13 the end portions of the wire blank will be bent 25 around projections 28 of the framing and brought towards each other and thereafter right angle bends C, will be formed therein. These right angle bends are formed by the free jaw ends of levers 13 cooperating with blade 38 to cause the 30 wire to be pressed within the grooves 16 of said jaw ends and cooperating with the projection or stud 41 to cause the wire to be pressed within the grooves 16' of the spaced opposed extremities 39 of said jaw ends. The wire ends so formed are 35 spaced apart by said stud or projection 41 and remain so spaced apart during engagement with the twister head to be described, whereby said end bends C will have the outer portions thereof twisted together to form an outer twisted shank 40 portion and will have the inner portions thereof retained spaced apart to form a branched or V-form inner shank portion which in the present instance is somewhat longer than said outer twisted shank portion. The projection 41 has its opposite lateral faces converging or tapered and the blade 38 has adjustable slot and bolt connection 38' with the frame head 37, this adjustment providing means for adjusting the parallelism of the spaced wire ends so that these wire 45 ends may be more readily engaged with the aperture of the twister head.

In the twisting of the spaced wire ends to form the shank of the hanger, a transverse twister carriage 44 is moved inwardly and outwardly by 55 means of a cam 45 upon shaft 19, said cam having a suitably shaped groove wherein works a roller 46 of lever 47, to vibrate said lever upon its fulcrum shaft 23, the free end of the lever having a rod 48 connecting it with lever 49, fulcrumed upon shaft 50, the other arm of said lever having a rod 51 connecting it with the twister carriage.

This carriage has a shaft 53, having bearings in the framing at 54, one bearing at each side of the carriage, the latter at its other end sliding 65 upon the framing at 55. The twister shaft 56 upon said carriage bears at its inner end the twister head 57, said head being provided with a diametric groove, wherein fit slides 57', formed with complementary recesses to provide a cone-shaped recess leading to the aperture of said head, said recess serving as a guide for the spaced wire ends into said aperture. These slides have a slot and bolt adjustment to accurately gage the said aperture for size. The twister head has 70 a key-way for four-fifths of its length, engaging 75

the key of pinion 58, said pinion meshing with gear 59, the latter being rotated one-fourth in one direction to rotate the pinion to give the desired twist to the shank wires, being then rotated one-fourth reversely to normal position. This rotation is given by means of a cam 60, on the shaft 19 aforesaid, said cam engaging bell-lever 61, having operating connection 62 with the shaft 63 of gear 59.

During the retraction of the twister carriage, 85 a hook forming means is brought upwardly to position to engage the extremity of the longer of the shank wires to form the same into a hook. This hook forming means comprises a rotary head 64, carrying upper rollers 65 and 66, both 90 of which are eccentric relative to the shaft 67 of said head. These rollers or projections 65 and 66 have the major portions thereof located both upon one semi-circular half of a face of the rotary head 64, whereby the hook is enabled to be 95 formed by a lesser rotary movement of said head than if said rollers were oppositely eccentric to the axis of rotation of said head, to thereby speed up the operation of the machine and produce more hangers in a given time, and the hook 100 is better released upon reverse rotation of said head in that said rollers move more directly away from the hook in such release. This head being brought upwardly to position as stated, the extremity of the longer of the shank wires lies 105 positioned between said rollers, whereupon said head is rotated counter-clockwise approximately one-half around. At the same time that the rotary head 64 is brought upwardly to position as stated, an abutment device 68 is brought to 110 position against the twisted shank D. During the first part of the rotation of the head 64, the eccentric roller 65 bears against the end portion of the longer wire end to form an initial bend in the wire in an oblique direction relative to the 115 shank D. The rotation of the head being continued, eccentric roller 66 acts to bend the wire end portion around the roller 65 to form the complete hook, of which said initial bend is a part, both rollers pushing in opposite directions 120 against the wire end portion in forming the hook.

The rotary head is now moved clockwise or retracted and at the start of this retractive movement the hook is released, both rollers leaving the hook. At this time also the levers 13 are 125 started back in their retractive movement, thereby completing the release of the hanger, which is then gripped by the delivery means to be described. The rotary hook-forming head is mounted at the upper end of a vertical shaft 67, 130 said shaft being moved upwardly to active position by cam 70, engaging a roller 71' of lever 71, said lever having a forked free end engaging between the arms of a yoke 72, loose upon said shaft, the latter having upper and lower collars 135 to maintain said yoke in proper position upon the shaft. A spring 73' acts to hold lever 71 against cam 70, and also to retract shaft 67 to down position with head 64 out of action.

The abutment device 68 is carried at one end 140 of a lever 68', having link connection 68'', with said lever 71. At the start of the reverse rotation of the head 64, the hook forming means including said head is started downwardly, thereby admitting of some release of the hook prior 145 to disengagement of the rollers 65 and 66 therewith, and avoiding any deformation of the hook in said release.

The main power shaft 20 drives a shaft 74 by bevel gears 75, the shaft 74 bearing the cams 150

70 and also a cam 76, the latter operating a lever 77, fulcrumed at its lower end at 78, said lever having a roller 79 bearing on said cam.

The shaft 67 of the hook forming head is rotated back and forth or oscillated by means of a pinion 80, keyed to said shaft and having supporting bearings in the framing adapted to permit the vertical reciprocation of said shaft, said pinion being engaged by segment gear 81, pivoted at 10 82 and the tail arm of which has pivotal connection with a link 83, the opposite end of said link being pivoted to the upper end of the lever 77.

The step by step operation of the parts comprises the delivery of the blank, the operation of 15 the levers 13, the operation of the twister and the operation of the hook forming means, in the order stated, the pick-up means for delivery of the completed hangers being actuated between said operations without interfering with the rapid 20 continuous order of the operations, a complete hanger being turned out and delivered for each rotation of the shaft 19.

Cam 45 operating the wire bending levers 13, through a concentric portion thereof, holds said 25 levers in closed position during the twisting and hook forming operations and releases the hanger at the time the delivery mechanism picks up the hanger.

The hangers being completely formed as stated 30 are picked up one at a time from their horizontal position on the bed of the machine, moved through an arc of about forty five degrees and placed upon an overhead horizontal rack 84 having vertical support 84' by the delivery mechanism as follows:

Parallel opposite spaced lever fingers 85 are fulcrumed at their inner ends at 86 centrally of a carrier loop 87, said loop having opposite parallel branches or arms 88, each carried by 40 a horizontal stub shaft 89, the stub shafts being aligned and given a vibratory movement to move said loop and fingers through an arc of about forty five degrees by means of crank arm 90, upon shaft 23, said arm having a connecting rod 91, 45 with a crank arm 92, upon one of said stub shafts.

Means are provided to separate and release the lever fingers 85 as they arrive at the limit of their downward movement so that they may engage or grip the twisted shank of the hanger 50 through the action of their connecting spring, and to separate and release said fingers as they arrive at their upward limit of movement, in order to deposit the hangers upon the rack 84, the loops of the hangers being engaged with said 55 rack, this means being as follows:

An angle lever 93 is pivoted in bearings 94 of the bridge arm of the carrier loop 87, the tail arms 93', 93'' of said angle lever contacting with abutments 95 and 96 at the times stated to 60 move the other arm of the angle lever axially, thereby moving a crank lug 97 upon said arm to work a slide 98 fitting in bearings between the root ends of said fingers, toggle levers 99 having the meeting ends thereof pivoted to the slide 65 and the outer ends thereof pivoted respectively to said fingers. The slide 98 is preferably made with a recess intermediate of its length wherein the crank lug 97 engages. The lever fingers 85 are provided with jaw faces 100, held normally in 70 contact by the aforesaid spring, designated 101.

I claim:—

1. In a machine for making wire garment hangers, means for bending wire blanks into form having end bends spaced apart and for twisting said spaced end bends in part together to form

an outer twisted shank portion including a stationary former device located between and separating the inner portions of said end bends during the twisting to make a V-form bend in the shank at the inner portion thereof.

80

2. In a machine for making wire garment hangers, means for bending wire blanks into form having end bends spaced apart and for twisting said end bends in part together to form an outer twisted shank portion and for retaining said end bends in part spaced apart and making an inner V-form shank portion, said means including a stationary former device located between and separating the inner portions of said end bends during the said twisting.

85

3. In a machine for making wire garment hangers, means for bending wire blanks into form having end bends spaced apart and for twisting said end bends in part together to form an outer twisted shank portion and for retaining said end bends in part spaced apart and making an inner V-form shank portion, said means including a stationary former device located between and separating the inner portions of said end bends during the said twisting.

90

4. In a machine for making wire garment hangers, means for bending wire blanks into form having end bends spaced apart and for twisting said spaced end bends in part together to form an outer twisted shank portion, including wire bending levers having spaced opposed free jaw ends and a stationary former device located between and separating said opposed jaw ends and separating the inner portions of said end bends during the twisting to make a V-form bend in the shank at the inner portion thereof.

105

5. In a machine for making wire garment hangers, means for bending wire blanks into form having right angle end bends and for twisting said end bends in part together to form a shank and for locking the bending means in clamping position prior to the twisting including wire bending levers having spaced opposed free jaw ends provided with notches having right angle extensions and a former device located between and separating said opposed jaw ends and separating the roots of said end bends during the twisting, and a stationary head having a 120 blade engaging said notches.

115

6. In a machine for making wire garment hangers, means for bending wire blanks into form having right-angle end bends and for twisting said end bends in part together to form a shank and for locking the bending means in clamping position prior to the twisting including wire bending levers having spaced opposed free jaw ends provided with notches having right-angle extensions, and a former device located between and separating said opposed jaw ends and separating the roots of the end bends during the twisting, and a stationary head having a blade engaging said notches, said former device being tapered and said blade being adjustable to adjust the parallelism of said end bends prior to the twisting.

130

7. In a machine for making wire garment hangers having means for bending wire blanks into hanger form having end bends of different lengths, means for twisting said end bends in part together to form a twisted shank, and means for bending the end portion of the longer of said end bends into hook form including a rotary head and two projections upon said head and

140

145

150

both of which are eccentric to the axis of rotation of said head; the major portions of both of said projections being located upon one semi-circular half of a face of said head, whereby the hook 5 is enabled to be formed by a lesser rotary movement of said head and the hook is better released upon reverse rotation of said head.

8. In a machine for making wire garment hangers having means for bending wire blanks 10 into hanger form having end bends of different lengths, means for twisting said end bends in part together to form a twisted shank and means for bending the end portion of the longer of said end bends into hook form including a rotary 15 head and two rollers upon said head and both of which are eccentric to the axis of rotation of said head; the major portions of both of said rollers being located upon one semi-circular half of a face of said head, whereby the hook is enabled to be formed by a lesser rotary movement 20 of said head and the hook is better released upon reverse rotation of said head.

9. In a machine for making wire garment hangers having means for bending wire blanks 25 into hanger form having end bends of different lengths, means for twisting said end bends in part together to form a twisted shank including a reciprocatory twister carriage, and means for bending the end portion of the longer of 30 said end bends into hook form including a rotary head and two projections upon said head and both of which are eccentric to the axis of rotation of said head; an abutment device, and means operating during the retraction of the twister carriage

35

carriage to move said head upwardly to engage said wire end portion between said projections and to simultaneously move said abutment device upwardly to engage said twisted shank, to thereafter rotate said head to form the hook and to rotate said head reversely and move said head and said abutment device downwardly out of the way of the twister carriage in the next forward movement of the latter.

80

10. In a machine for making wire garment hangers having means for bending wire blanks into hanger form having end bends of different lengths, means for twisting said end bends in part together to form a twisted shank including a reciprocatory twister carriage, and means for bending the end portion of the longer of said end bends into hook form including a rotary head having two rollers both of which are eccentric to the axis of rotation of said head; the major portions of both of said rollers being located upon one semi-circular half of a face of said head, an abutment device, and means operating during the retraction of the twister carriage to move said head upwardly to engage said wire end portion between said rollers and to simultaneously move said abutment device upwardly to engage the same with said twisted shank, to thereafter rotate said head to form the hook and to rotate said head reversely and move said head and said abutment device downwardly out of the way of the twister carriage in the next forward movement of the latter.
